WILLIAM C. HUEBNER, OF CHICAGO, ILLINOIS, ASSIGNOR TO HUEBNER-BLEISTEIN
PATENTS COMPANY, OF BUFFALO, NEW YORK

PHOTOGRAPHIC PRINTING APPARATUS

Application filed March 31, 1928. Serial No. 266,432.

This invention relates to improvements in photographic printing or composing apparatus for producing contact photographic prints in any required predetermined positions upon print-receiving surfaces or elements, such as the sensitized surfaces of sheet metal press plates which are used in mechanical printing presses for printing in one or several colors.

Such apparatus usually comprises a support or holder for the sensitized press plate, a support or holder for holding a negative or positive printing plate, sheet or other element (hereinafter called the printing element) in face to face relation with the sensitized surface of the press plate (hereinafter called the print receiving element) means for causing intimate uniform contact between the faces of said elements, adjusting means for causing relative movement between said elements parallel with the faces thereof to enable prints to be made in desired predetermined relations or locations on the print receiving element, and means for causing a relative movement of said elements toward and from each other for placing them in contact and separating them to permit clearance during said relative parallel movements therebetween. The printing is effected by exposure of the sensitized surface to a suitable source of light through the image or printing element.

In the particular type of apparatus under consideration, the relative parallel movements between the print receiving and printing surfaces are effected by vertical and horizontal adjustments of the latter in a plane parallel to the surface of the former so that an image on the printing plate or element can be located opposite different portions of the print receiving element, while the latter remains in its initial location on its holder or support.

One object of the invention is to provide an improved novel photographic printing or composing apparatus of relatively simple, compact and inexpensive construction.

Other objects of the invention are to provide such apparatus with a novel, adjustable carriage for the printing plate or element,

and also to provide a carriage of this sort which is adapted to support a relatively large printing element either in the form of a rigid plate or flexible sheet, whereby large subjects can be printed on the print receiving element for use in poster work and the like; also to provide, in connection with a swinging support for the print receiving element, novel stop and locking means for arresting said support when moved to printing position and locking it in such position during the printing operation; also to provide a relatively simple clearance mechanism for effecting separation between the printing and print receiving surfaces while the swinging support is locked to permit adjustments of the printing element to new locations relatively to the print receiving element; and also to improve photographic printing apparatus of the character described in the other respects hereinafter set forth and claimed.

In the accompanying drawings:—

Fig. 1 is a front elevation of a photographic printing apparatus embodying my invention, the swing frame or support for the sensitized print receiving plate or element being omitted.

Fig. 2 is a fragmentary front elevation thereof, with the sensitized plate support in printing position, portions of said support being omitted for the sake of clearness.

Fig. 3 is a transverse section of a detail of the stop means and locking mechanism for the sensitized plate support, taken on line 3—3, Fig. 12.

Fig. 4 is a front elevation on an enlarged scale, of a portion of the main frame with the carriage for the printing plate or element mounted thereon.

Fig. 5 is a fragmentary, horizontal section of the apparatus on an enlarged scale, partly on the line 5—5, Fig. 1 and with a portion of the sensitized print receiving element and its holder in operative or printing relation to the printing element.

Figs. 6 and 7 are respectively a transverse vertical section and a horizontal section of the locking mechanism for holding the vertically movable printing element carriage in any position to which it is adjusted.

Fig. 8 is a fragmentary, vertical section of said lock mechanism on line 8-8, Fig. 7, in a plane at right angles to Fig. 6.

Fig. 9 is a fragmentary, transverse, vertical section, on an enlarged scale, on line 9-9, Fig. 1, of the printing element carriage and the adjusting mechanism.

Fig. 10 is a similar view thereof, on a still larger scale on line 10-10, Fig. 1.

Fig. 11 is a fragmentary face view of the apparatus with a relatively large printing element and its holder mounted thereon.

Fig. 12 is a fragmentary, rear view, on an enlarged scale, of a portion of the support for the print receiving element, showing the mechanism for effecting clearance between said element and the printing element.

Fig. 13 is a fragmentary, transverse section thereof, on line 13-13, Fig. 12.

Fig. 14 is a vertical section of the holder of said support showing suitable means for mounting and stretching a flexible sensitized plate or element thereon.

The invention is illustrated in connection with a photo composing or printing apparatus of the vertical type in which the printing and print receiving surfaces or elements are disposed in parallel vertical planes.

The apparatus shown in the drawings comprises generally an upright stationary main frame or support A on which is mounted for vertical movement a carriage B on which the transparent printing plate or element X is supported. The printing element X is in turn adjustable horizontally on the carriage B.

A print receiving surface or element Y such as a sensitized, flexible, sheet metal plate, is mounted and stretched taut on a holder C, attached to or forming part of a swing frame or support D hinged or pivoted at one side of the main frame A so as to be swung either into an operative position in front of said frame A with the element Y in parallel relation to the printing plate X or into an inoperative position extending in angular relation to said frame A to permit access to said elements X and Y. The swing frame is provided with mechanism which, when said frame is in operative position, is used to place the print receiving element Y into contact with the element X for printing, and out of contact therewith for effecting a clearance between said elements, to permit the element X to be adjusted to different predetermined locations with reference to said element X.

A suitable source of light, not shown, may be confined within a hood x arranged at the back of the printing plate X for effecting the exposure of an image thereon through the same upon the sensitized plate Y.

The main frame A is preferably formed of a pair of parallel, spaced uprights or hollow posts 10 connected at the upper ends by a

cross member 11 and adjacent their lower ends by a cross member 12. These lower ends of said uprights are preferably secured to brackets or castings 13 and 14 forming part of a stationary base or platform 15. Each of the uprights 10 is formed with a vertical channel or recess 16 extending substantially throughout its length. A slide bar 17 engages or fits in this recess and is confined for vertical sliding movements therein by overhanging retaining strips 18, fixed to the forwardly projecting side edges of the uprights. On a forwardly projecting, reduced rib or portion 19 of the slide bar, there is secured a scale 20 divided into any desired units of measure, such as inches, by graduations 21.

The carriage B is slidably connected to the slide bars 17 to move up and down relatively thereto, to effect a primary coarse vertical adjustment of the printing element X, these movements being indicated by the scales 20. The carriage can also be locked to said bars 17 and the bars and carriage B adjusted vertically relatively to the frame A, these movements being indicated in small fractions of said units of measure, as will be explained, to effect a final fine adjustment of the said element X.

The carriage B includes a pair of parallel, spaced, horizontal cross bars or members 25 and 26 which extend across the main frame in front of the uprights 10 with their ends preferably extending laterally beyond said uprights, see Fig. 1. The lower bar 26, see Fig. 1, is provided opposite the slide bars 17 with a pair of rearwardly extending slides or blocks 27 of channel cross section. Each slide 27 is disposed with its legs 28 straddling the projecting rib 19 and scale 20 of the respective bars 17 and slidably engage in parallel lengthwise grooves 28a in said bar, being confined therein by overhanging strips 29. Each block is mounted on a pivot stud 30 on the rear of the bar 25 and is arranged to turn thereon to a limited extent to prevent binding in the grooves 28, being confined by opposed parallel retaining strips 31 on said bar 25 and which engage corresponding flanges 32 on said slide blocks 27. The upper bar 25 is provided with a pair of similar slides or blocks 33, also mounted and operatively engaging the slide bars 17 in substantially the manner just described. One of the carriage bars, for example, the lower bar 26, is provided with a slide bar 35 similar to the slide bars 17, and which slidably fits in a lengthwise channel or recess 36 therein, being held in position by strips 37. A forwardly projecting lengthwise rib 38 on said slide bar carries a scale 39 divided into units of measure by graduations 40.

The printing plate or element X is disposed so as to extend vertically between the carriage bars 25 and 26, being mounted for this purpose on a rigid holder or frame re-

movably secured at top and bottom to attaching slides or members 44 and 45 mounted and arranged for longitudinal movements on the respective bars 25 and 26.

5 When a glass plate X or other substantially rigid element is to be used, a holder 46, as shown in Figs. 1, 5 and 10 can be employed, while when a flexible printing element, such as a paper negative or positive, or 10 a film is to be utilized, a holder 46a, Fig. 11 is preferably utilized. The latter is especially desirable for large poster work and reduces the expense and difficulties incident to the use of large glass plates.

15 The holders 46 and 46a comprise suitable side and top and bottom members surrounding a printing opening 47 over which the printing plate is detachably secured by suitable blocks 47a and into which the hood x of 20 the light projects.

To enable suction to be used for withdrawing air from between the contacting surfaces of the elements X and Y, each holder is provided with a connection 48 for a hose or passage 49, which communicates with a suction chamber or space 50 formed by a ledge 51 extending around the plate X in spaced relation thereto. The ledge 51 is provided with a sealing gasket 52 which engages the face of 30 the print-receiving element Y.

35 The holder 46a is substantially like the holder 46 except that it is provided with adjustable clips 53 for gripping the edges of the flexible printing element X and stretching said element taut and smooth.

The smaller holders 46 are detachably connected in predetermined relation to the attaching slides 44 and 45 by centering studs or dowels 54 on the latter which fit in holes in 40 said holders, while the larger holders 46a are centered on similar studs 54a.

45 The studs 54, 54a and the holes in the respective holders are placed in definite predetermined locations so that all holders for each set of studs are located in exactly the same position on the attaching slides 44 and 45. When the desired holder has been attached to said slides 44 and 45, it is locked in position by swinging fingers or catches 55 50 which engage over the edges of the holder, see Figs. 1, 10 and 11. The holders for the printing elements can, however, be of any other suitable construction.

55 Means are provided for varying the distance between the bars 25 and 26 of the carriage B in order to accommodate printing plates and holders of different vertical dimensions. The means shown, see Figs. 1, 4 and 9, includes a horizontal operating shaft 60 60 journaled at each end in hollow bearing brackets 57 fixed to and projecting upwardly from the ends of the bar 25. Within each bracket 57 the shaft 56 is provided with a spiral gear 58 meshing with another spiral gear 59 also bearing in said bracket. These

gears 59 are splined on and arranged for endwise movement relatively to a pair of vertical shafts 60, one of which is arranged at each side of the apparatus. Each shaft 60 is provided with upper and lower, oppositely 70 screw-threaded portions 61 and 62 which respectively operatively engage in threaded sleeves or nuts 63 and 64. The sleeves 63 are rigidly secured in fixed brackets 65 projecting rearwardly from the upper carriage bar 75 25, while the sleeves 64 are similarly disposed in corresponding brackets 66 on the lower carriage bar 26, see Figs. 4 and 9.

It will be seen that upon rotating the shaft 56, as by a crank 68 on one end thereof, the 80 shafts 60 will be caused to rotate in unison, and through their engagement in the sleeves 63 and 64, will effect relative adjustments of or vary the distance between the bars 25 and 26.

85 Preferably, when the carriage bars are to be adjusted for mounting, a holder thereon, the lower bar 26 is temporarily locked to the vertical scale bars by means to be described, thus causing all of the motion from the screw 90 shafts 60 to be applied to the upper scale bar 25. If desired, however, the bars can both be simultaneously actuated by the screw shafts 60 by leaving the bar 26 unlocked.

95 In order to indicate or observe the amount of the adjustment of the bar 25 relatively to the bar 26, the shafts 60 are each provided with a part movable past a vertical scale bar 69 fixed to the adjacent upright 10 of the main frame A. Each indicating part consists of 100 an arm 70 swivelled on and prevented from endwise movement relative to its shaft 60 and having its free end 71 bifurcated to slidably embrace an edge or guide portion 72 of the adjacent scale bar 69. In this manner, the indicating arm 70 can travel along the scale bar without binding thereon. A suitable line or pointer 73 on each arm cooperates with the graduations 74 on the scale to clearly indicate 110 the adjustments of the carriage bars. When using the described indicating means, the movement of the arms 70 is observed and the adjustment of the bar 25 is stopped when the pointer has travelled half the required distance, as owing to the fact that the lower bar 115 is held stationary, the action of the opposite screw thread 61 and 62 causes said bar 25 to travel twice the indicated distance.

120 The vertical scales 20 and the horizontal scale 40 are constructed substantially as in my copending application for Letters Patent No. 120,179, filed July 7, 1926, now Patent No. 1,668,592, granted May 8, 1928, and entitled Precision registering and adjusting mechanisms for photographic printing and other machines.

125 Each scale, see Figs. 4, 5 and 10, comprises a plurality of separate blocks 75 and 76 arranged in staggered relation, and suitably clamped in a holder 77 open at one side, the 130

blocks forming what may be termed a rack which is exposed at said open side. The blocks are accurately formed to a standard unit of measure, in the present instance being one-half inch in width, thus providing a precise scale to which the part of the apparatus moving relatively to said scale can be coupled in exact predetermined position, for effecting a primary coarse adjustment of said part.

The upper attaching slide 44 is provided on its rear face with opposed guide members 79 slidably engaging the opposite edge portions of a forwardly projecting T-shaped track portion 80 on the upper carriage bar 25. The lower attaching slide, however, is provided with a pair of spaced slide blocks 81, similar to the slide blocks 27 and 33 before mentioned, and the legs 82 of which straddle the scale bar 39 and projecting portion 38 of the slide bar 35 and slidably engage in longitudinal grooves 83 in said bar. The slide blocks are held in position by retaining strips 84.

It will be seen from the foregoing that the carriage B is a rigid or unitary structure composed of bars 25 and 26 adjustably tied together by the screw shafts 60, and when in use, also by a holder 46 or 46a. This structure as a whole is movable vertically upon the main frame, while the holder for the printing element X connected to the attaching slides 44 and 45 is movable horizontally along the carriage by the sliding connections between said slides and the carriage bars. Thus, the printing element can be moved in a plane parallel with its face by appropriate horizontal and vertical adjustment to any desired location within the range of the apparatus, or in other words, within the length of the said carriage bars and said screws 60 respectively, and any size holder within these limits can be mounted on said carriage.

Any suitable means may be provided for effecting the primary horizontal adjustments of the printing element holder relatively to the carriage B and also for effecting the primary coarse vertical adjustment of the carriage as a whole. For the former, in the construction shown, the attaching slide 45 is provided with a depending lug or part 85, see Figs. 1 and 10, in which is journaled a short, horizontal, transverse shaft 86 formed at its front end for the reception of a suitable operating crank 87. Fixed on the rear end of said shaft is a pinion 88 which meshes with a horizontal rack 89 on the lower edge of the carriage bar 26. By rotating the shaft 86 in one direction or the other, the attaching slides 44 and 45 with the printing element holder secured thereon can be adjusted lengthwise of the carriage B for the desired distance in inches or half inches, the adjustment being shown, for example, by a

pointer 90 arranged in an opening 91 in the bar 45 and cooperating with the graduations on the scale 39.

After this adjustment has been effected, the parts are locked to the slide bar 35, after which, if required, a further fine adjustment, in small fractions of an inch, is made. The locking means shown for the aforesaid purpose comprises a locking member 95, Fig. 10, arranged in a cavity in the lug 85 and provided with a pair of upstanding fingers 96. The member 95 is formed with rack teeth 97 with which meshes a pinion 98 formed on a shaft 99 journalled in said lug and provided with a handle for turning it. Upon rotating said shaft 99 and pinion 98 in one direction, the member 95 is raised to the position shown in said Fig. 10, with the fingers 96 extending through a hole in the slide block 81 into interlocking relation with the adjacent blocks 76 of the scale 39. The fingers are formed to exactly fit between said scale so that the parts are thus rigidly locked together.

The fine or fractional horizontal adjustment of the printing element X is now obtained by the following means, see Figs. 1, 4 and 5. Fixed to one end of the lower carriage bar 26 is a bracket 100 having a split clamp formed with a threaded hole 101 in which a longitudinal horizontal screw shaft 102 engages and which extends parallel with said bar 26. The inner end of the screw shaft 102 rotatably bears in and is prevented from endwise movement relatively to a lug 103 on the adjacent end of the horizontal slide bar 35. The outer end of the shaft is fashioned for the reception of an operating crank 104, and adjacent this end the shaft is provided with a fixed scale drum 105 divided on its periphery by graduations 106 into one hundred equal divisions. These graduations register with a fixed pointer 107 on the bracket 100. The threaded portion of the shaft 101 is provided with a predetermined number of threads per inch or unit of measure, for example, ten. When the shaft 102 is rotated it moves endwise in the bracket 100 and causes a corresponding movement of the slide bar 35 relatively to the bar 26. Therefore, each revolution of the shaft adjusts the bar 35 one-tenth of an inch, this travel being indicated by the drum 105, while fractions of each revolution are indicated by said drum in thousandths of an inch.

Before operating the rack and pinion coarse adjustment of the attaching slide, the screw shaft 102 is turned to place the drum 105 at zero so that the full unit adjustments are correctly performed, after which the desired fractional adjustments are made.

The coarse adjusting means for the carriage B includes a horizontal operating shaft 110 journalled in depending portions 111 of the carriage slide blocks 27, and also in a

similar part of the bracket 100. Alongside each part 111 the shaft is provided with a fixed pinion 112 which meshes with a vertical rack bar 113 on the adjacent main carriage upright 10.

By appropriate manipulation of the shaft 110, the carriage B can be raised or lowered, the adjustments thereof being indicated either by the scales 69 and pointers 71, or by the scales 20 and cooperating pointers 114 on the carriage.

The carriage is preferably connected by chains 115 passing over sprockets 116 to counterweights concealed within the uprights 10. When the vertical coarse adjustment has been made, the carriage B is locked to the vertical slide bars 17 on the main frame by suitable means. The means shown for this purpose, see Figs. 4, 6, 7 and 8, comprises a horizontal rock shaft 120 journalled and held from endwise movement in the slide parts 111 and in the bracket 100. Adjacent each of the parts 111, the shaft 120 is provided with a fixed sleeve 121 having thereon a rearwardly extending oblique cam or part 122 operatively engaging in a complementary groove 123 in a bolt 124. This bolt is arranged in a casing 125 fixed to the side face of the depending slide part 111. Each bolt, see Fig. 8, is provided with spaced fingers 126, the bolts being simultaneously projected laterally through holes in said parts 111 for placing said fingers into or out of locking engagement with the blocks 76 of the adjacent vertical scales 26 upon appropriate manipulation of said rock shaft 120, as by the handle 127.

The fine vertical adjusting mechanism for the carriage B is substantially like the horizontal fine adjusting means described and comprises a horizontal adjusting shaft 130 extending parallel to and in rear of the main frame and journalled at each end in a fixed bearing bracket 131 on the adjacent upright 10. Within each bearing 131 said shaft 130 is provided with a spiral gear 132 which meshes with a similar gear 133 fixed to the lower end of a vertical shaft 134 also journalled in said bearing jacket. A part of each shaft 134 is provided with a screw portion of ten threads per inch, this portion being received in a threaded split aperture in a bracket 135, which has a lateral part 136 by which it is fixed to an edge of the adjacent slide bar 17.

A drum 137 fixed to the upper end shaft 134 is provided with one hundred equal graduations 138 movable past a fixed pointer 139 on said bracket 135. Thus by turning the shaft 130, as by crank 140, the shafts 134 are simultaneously rotated and the two slide bars 17 are moved endwise in unison carrying with them the carriage B through the medium of the locked slides 27. If desired, an expansion spring or the like 141 can be disposed

around each shaft 134 between a fixed collar thereon and the bracket 135 thus aiding in overcoming the inertia of the carriage and relieving to some extent the weight thereof when making adjustments.

The swing frame or support D for the sensitized sheet metal plate or print-receiving surface, see Figs. 2, 12 and 13, is formed of a pair of spaced uprights 140 and 141, of substantially channel cross section rigidly connected at their upper and lower ends by cross bars 142 and bounding an opening 143, over which the element Y and its holder C are arranged.

A vertical post or member 144 mounted at its lower end in a forwardly extending part of the main frame bracket 14 and at its upper end in a bracket 145 extending from said frame A serves as a pivot for the reception of spaced upper and lower hinge members 146 fixed to the upright 141 of the swing frame. The swing frame D can be turned about the axis of the pivot 144 from a position extending at an angle to the main frame to an operative position in front of and parallel therewith for placing the print receiving element Y opposite the printing element X.

As the swing frame D moves into said operative position it engages suitable stop and centering or positioning devices on the main frame A for bringing the swing frame to rest in exact predetermined relation to said frame A, suitable locking means being provided for rigidly holding the swing frame in such relation.

The stop and centering means used comprises two horizontal fixed studs 148 projecting forwardly respectively from the lower main frame bracket 18 and from an upper bracket 149 on said frame. These studs 148 are received in closely fitting bushings 150 on the swing frame, these bushings being preferably adjustably mounted in eccentric sleeves 151 and 152, whereby they can be accurately alined with the studs 148. A projecting stop sleeve 153 surrounding each bushing 150 is adapted to abut against an enlargement or stop face 154 on the corresponding stud to arrest and correctly position the swing frame.

The locking means for the swing frame consists of a pair of latches 156 each of which is pivoted at one end of its ends on the swing frame adjacent and at one side of one of said studs. The latch extends across the upper side of said stud, being movably arranged in the path thereof so as to be engaged and lifted by a cam end or part 157 on the stud as the latter passes through its corresponding bushing 150. As the swing frame comes to rest against the stops 154, each latch drops and fits snugly into a notch 158 in the stud, thus locking the swing frame in operative position. Preferably the latches 156 are

pivottally connected to an upright link 159 provided with an operating handle 160 which projects laterally through a slot 161 in the swing frame. The handle normally rests by gravity on the lower edge of the slot 161 for holding the latches in position to be engaged by the studs 148. The handle 160 and link 159 afford appropriate means for simultaneously lifting and disengaging from the studs 148 both latches when the swing frame is to be released.

The plate holder C can be of any suitable construction, being formed, in the construction shown, of opposite spaced uprights 165 rigidly connected by top and bottom cross channel bars 166 and 167.

The upper and lower edge portions of the sheet metal or other flexible element Y are secured between pairs of reinforcing and gripping bars 168. The upper bars are readily held in the usual inclined jaws or blocks 169 arranged in the channel 166, while the lower bars are held in a similar manner in vertically adjustable blocks 170 slidably arranged in guides in the lower channel bar 167. These blocks are adjusted by screws 171 having threaded engagement in a fixed web on said channel bar so as to draw the flexible plate taut over the inner edges of the channel bars. The flexible element Y is preferably, though not necessarily reinforced by a flat, sectional backing plate 172, the face of which is rigidly held in the plane of the back of said element by a cross bar 173 fixed to the side members of the holder, and which bears against spaced vertical strips 174 on said backing plate. This reinforcement is omitted from Fig. 2 for the sake of clearness.

The plate holder C is suitable secured on a sub-frame or carrier 175 consisting of parallel top and bottom strips 176, and similar opposite side strips 177. This carrier is movably mounted on the swing frame to shift away from and towards the same a predetermined or fixed distance in a direction perpendicular to the face of the print receiving element Y for placing said face into and out of contact with the printing element X for printing, and for affording clearance between their faces when adjusting the printing element on its carriage B. For this purpose the carrier 175 is provided at each corner with a rearwardly extending, fixed stud 178 which is received in a sleeve portion 179 of a bearing bracket 180 fixed on the rear face of the adjacent corner of the swing frame. Rotatably journaled and prevented from endwise movement in said bracket is a sleeve 181 which is interiorly threaded for engagement with the inner threaded end of the stud 78. Fixed on the sleeve 81 is a sprocket wheel 182. One of the sleeves 181 is provided with a crank 183 for rotating it, and all of the sprockets, as well as a tight-

ener sprocket 184 are operatively engaged by an endless sprocket chain 185, Figs. 2, 12 and 13. By manipulating the crank 183 in the proper direction, the sprockets are all rotated and screw studs 178 projected or retracted in unison by means of the sleeves 181. In the position of the parts shown in Fig. 13, the print receiving element is in the printing plane, this position being determined by any suitable adjustable stops, as indicated at 186, while the clearance position is obtained by the engagement of the rear of the carrier 175 with the front face of the swing frame.

The photographic printing apparatus herein described is of relatively simple and compact construction and is adapted for the efficient production of relatively large work, owing to the fact that the carriage permits the use of large size printing plates or elements. The adjustments for mounting and positioning these elements can be easily and rapidly made. The locking means and clearance means for the print receiving element support are relatively simple and can be readily manipulated, while the swing frame, pivotally arranged as disclosed, permits ready access to the printing and print receiving elements for adjusting or changing one size for another. Moreover, the use of relatively large printing elements is also made possible by the disposition of the printing element holder at one side of or forwardly beyond the carriage, which in turn is forwardly or in front of and extends beyond the uprights of the main frame. In this way there is no obstruction to the use and adjustment of large printing elements.

I claim as my invention:—

1. In a photographic printing apparatus, the combination of a support for a sensitized print-receiving element, a holder on which a printing element is adapted to be mounted for supporting said printing element in predetermined relation to and in face to face printing contact with said print-receiving element, a carriage on which said holder is mounted and which includes spaced guide members, a slide bar mounted on and adapted for lengthwise movements relatively to one of said guide members, attaching means for connecting said printing element holder to said slide bar so as to move relatively thereto to effect a primary coarse adjustment of said holder along said guide member, means for locking said attaching means to said slide bar, means for moving said slide bar and said holder relatively to said guide member for effecting a final fine adjustment of said holder, and means for movably connecting said holder to said other guide member for movement relatively thereto during said coarse and fine adjustments.

2. In a photographic printing apparatus, the combination of a support for a sensitized

- print-receiving element, a holder on which a printing element is adapted to be mounted for supporting said printing element in predetermined relation to and in face to face printing contact with said print-receiving element, a carriage on which said holder is mounted and which includes spaced guide members, a slide bar mounted on and adapted for lengthwise movements relatively to one of said guide members, attaching means for connecting said holder to said slide bar so as to move relatively thereto to effect a primary coarse adjustment of said holder along said guide member, a stationary scale on said carriage for indicating such adjustments, means for locking said attaching means to said slide bar, a fine adjusting mechanism for moving said slide bar and said holder relatively to said guide member for effecting and indicating a final fine adjustment of said holder, and means for movably connecting said holder to said other guide member for movement relatively thereto during said coarse and fine adjustments.
3. In a photographic printing apparatus, a holder on which a printing element is adapted to be mounted, a support on which said holder is secured, a support for a print-receiving element pivotally mounted on said other support so as to swing to and from an operative position parallel thereto to position said print receiving element face to face with said printing element, a positioning stud on one of said supports, a bushing on said other support into which said stud fits when said swinging support is moved to operative position, a gravity latch disposed in the path of said stud, a part on said stud for lifting said latch when said stud enters said bushing, and said stud having a notch into which said latch drops to rigidly lock said swinging support in operative relation to said other support.
4. In an apparatus of the character described, the combination with a holder adapted to retain a printing element; of a carriage on which said holder is mounted, said carriage including spaced guide members; an attaching member lengthwise adjustably supported on each guide member, said attaching members being independent of each other; means for attaching the holder rigidly to one of said attaching members so as to move therewith as a unit; a main frame on which the carriage is supported; means for temporarily locking one only of said guide members to said frame in adjusted position; and means operatively connected to said guide members for adjusting the same relatively toward and from each other while the one of them is locked to said frame.
5. In an apparatus of the character described, the combination with a main frame having a stationary guide member; of a slide bar adjustably mounted on said guide member; a carriage; means for adjusting said carriage lengthwise of said guide member independently of said slide bar; means for locking said carriage to the slide bar in adjusted position; and additional means for adjusting the slide bar and the carriage while locked thereto, relatively to said guide member.
6. In an apparatus of the character described, the combination with a main frame; of a carriage adjustably mounted on said main frame to move in one direction; a slide bar adjustably mounted on said carriage to move in a direction transverse to the first named movement; a slide adjustably mounted on said carriage in a direction transverse to the first named direction, said slide being adapted to have a holder mounted thereon; means for adjusting said slide relative to the carriage and independently of said slide bar; means for locking said slide in adjusted position to said slide bar; and means for adjusting the slide bar relative to the carriage while the slide is locked to the slide bar.
7. In an apparatus of the character described, the combination with a main frame having a stationary guide member; of a slide bar mounted to move lengthwise of said guide member; a carriage slidably mounted on said guide member; a slide bar adjustably mounted on said carriage to move in a direction transverse to the line of movement on said guide member; a slide also adjustably mounted on said carriage to move in the same direction as the slide bar thereon; separate means for adjusting the carriage lengthwise of said guide member and the slide lengthwise of the carriage, respectively; means for locking the carriage to the first named slide bar and said slide to the second named slide bar, in adjusted positions, respectively; and additional means for adjusting each of the slide bars with the carriage and slide locked respectively thereto.
8. In an apparatus of the character described, the combination with a main frame; of a carriage slidably adjustable on said main frame in one direction, said carriage including parallel spaced guide members; a slide on each of said guide members and movable lengthwise thereof, said slides being adapted to retain a holder thereon; a slide bar lengthwise adjustable on one of said guide members; means for adjusting one of said slides relative to its guide member; means for locking said slide to the adjacent slide bar; and means for adjusting said slide bar relative to its respective guide member while the slide is locked thereto.
9. In an apparatus of the character described, the combination with a stationary frame; of a carriage adjustably mounted thereon to move in one direction; a printing element holder mounted on said carriage and positioned in a plane outwardly of said main frame and the carriage; a support for a print-receiving holder, said support being pivotally

attached to the frame; a print-receiving holder mounted on said support, the latter and the print-receiving holder being adapted to be brought into parallel relation with the printing element holder; means for adjusting said print-receiving holder toward and from the printing element holder to effect clearance therebetween; and means for effecting a relative shift between the printing element holder and the print-receiving holder in a direction at right angles to said line of movement of the carriage on the stationary frame.

10. In an apparatus of the character described, the combination with a guide member; of a slide bar mounted thereon; a slide adapted to support a holder, said slide being movable lengthwise of said guide member independently of the guide bar; means for locking said slide to the guide bar in various adjusted positions; and means for effecting movement of the slide bar lengthwise of the guide member while said slide is locked to the slide bar.

11. In an apparatus of the character described, the combination with a main frame; of a carriage adjustably mounted on said main frame to move in one direction, said carriage including parallel guide members adjustable toward and from each other for holders of different sizes; of a slide lengthwise adjustable on one of said guide members in a direction at right angles to said line of adjustment of the carriage, said slide being adapted to have a printing element holder secured thereto; a second slide mounted on the other guide member and to which the opposite end of said holder is adapted to be attached whereby both slides are movable in unison when a holder is in place; means for mechanically effecting adjustment of one of said slides relative to its guide member; and additional means for effecting a final lengthwise adjustment of said last named slide relative to its guide member.

12. In an apparatus of the character described, the combination with a main frame; of a carriage adjustable on said main frame in one direction, said carriage including a guide member extending at right angles to said line of adjustment; a slide slidably mounted on said guide member in a direction at right angles to said first named line of adjustment; means for effecting a relatively coarse adjustment of said slide relative to its guide member; and additional means for effecting a relatively fine adjustment of said slide relative to its guide member.

13. In an apparatus of the character described, the combination with a main frame; of a carriage slidably mounted on said main frame; two independent sets of means for separately effecting relatively coarse and relatively fine adjustments of said carriage relative to said main frame; negative-holding

means slidably mounted on said carriage in a direction at right angles to the line of movement of the carriage on the frame; and two independent sets of means for separately mechanically effecting relatively coarse and fine adjustments of said holding means on said carriage.

14. In an apparatus of the character described, the combination with a main frame having stationary guiding means for a carriage; of a carriage movable lengthwise of said means; means for relatively coarsely adjusting said carriage lengthwise of said guiding means; a member lengthwise adjustable on said frame and parallel to the line of movement of said carriage relative to the frame; means for locking said carriage to said member when in relatively coarsely adjusted position; and additional means for effecting relatively finer adjustments of said member while the carriage is locked thereto, relative to the frame.

15. In an apparatus of the character described, the combination with a main frame; of a carriage adjustably mounted on said main frame to move in one direction; an attaching slide adjustably mounted on said carriage to move in a direction transverse to the first named direction and to which a holder is adapted to be detachably secured; means for relatively coarsely adjusting said attaching slide relative to the carriage; means also adjustably mounted on said carriage to move in a direction transverse to said first named direction of movement of the carriage; devices for locking said attaching slide to said last named means in relatively coarsely adjusted position of said attaching member; and mechanism for relatively finely adjusting said means adjustably mounted on said carriage when the slide is locked thereto.

16. In an apparatus of the character described, the combination with a stationary main frame; of a carriage adjustably mounted on the main frame to move in one direction; a printing element holder mounted on said carriage and adapted to retain a printing element in one plane; a main support for a print-receiving holder also mounted on said main frame; a print-receiving holder adjustably mounted on said main support and adapted to hold a print-receiving element in a plane parallel to that of the printing element; means for adjusting said print-receiving holder toward and from the printing element holder to effect clearance therebetween, said means being mounted directly on said support and independent of the main frame; and means for effecting a relative shift in parallel planes between the printing element holder and the print-receiving holder in a direction at right angles to said line of movement of the carriage on the main frame.
